UNITED STATES PATENT OFFICE

2,546,075

BLADE AND JAW CONSTRUCTION FOR
CYLINDER FOLDING MECHANISMSArthur Meadowcroft, Chicago, Ill., assignor to
Chicago Rotoprint Company, Chicago, Ill., a
corporation of Illinois

Application October 9, 1947, Serial No. 778,846

6 Claims. (Cl. 270—71)

1

This invention relates to improvements in folding mechanisms of the type commonly employed in connection with printing presses for folding one or more sheets of paper. The present invention is more particularly concerned with improvements in rotary folding mechanisms in which a tucking blade is provided on the periphery of a collector cylinder to tuck a sheet of paper between a pair of clamping jaws which are mounted on the periphery of another cylinder. The clamping jaws are arranged to grip and fold a sheet of paper inserted therebetween by the tucking blade.

The present invention contemplates the provision of an improved type of tucking blade formed with a V-shaped tucking edge for insertion between the clamping jaws.

This invention further contemplates the provision of a resilient mounting for the tucking blade to yieldably resist displacement of the latter during gripping and folding engagement by the clamping jaws.

This invention further contemplates the provision of improved means for mounting and actuating the clamping jaws.

This invention further contemplates the provision of resilient inserts, preferably formed of rubber, mounted upon the clamping jaws to grip and fold sheets of paper inserted between the jaws.

Another object of this invention is to provide a hollow clamping jaw cylinder filled with loose particles of sound absorbing material, such as cork.

This invention embodies other novel features, details of construction, and arrangement of parts which are hereinafter set forth in the specification and claims, and illustrated in the accompanying drawings wherein:

Fig. 1 is a plan view illustrating a folding mechanism embodying features of this invention.

Fig. 2 is a sectional view taken along the line 2—2 of Fig. 1.

Fig. 3 is an enlarged fragmentary transverse sectional view showing a tucking blade positioned to insert a sheet of paper to be folded between a pair of clamping jaws.

Fig. 4 is a detail fragmentary plan view showing the clamping jaw cylinder.

Fig. 5 is a detail perspective view showing the construction of the clamping jaw face plate.

Fig. 6 is an enlarged fragmentary transverse sectional view, similar to Fig. 3, illustrating a modified form of the invention.

Referring now to the drawings for a better 55 set of jaws serving to coat with a tucking blade

2

understanding of this invention, and more particularly to Figs. 1 to 5 therein, a folding mechanism is shown as comprising a collector roll 7 secured on a shaft 8 which is mounted at its ends in suitable bearings (not shown) provided on side frame members 9 and 11. A jaw cylinder 12 is journaled at its ends in bearings 13—13 provided on the frame members 9 and 11 to coat with the collector roll 7 in folding sheets of paper 14.

5 While it is contemplated that the collector cylinder 7 and jaw cylinder 12 may be any suitable diameter, it is essential that these cylinders are driven at the same peripheral speed and in timed relation by any suitable means (not shown).

The collector cylinder 7 is provided with three tucking blades 16 formed with V-shaped tucking edges 17 projecting outwardly from the periphery of the cylinder. While the collector cylinder 7 is shown provided with three tucking blades 16 equally spaced about the periphery of the cylinder, it is contemplated that the collector cylinder could be provided with one or more tucking blades, if desired.

Each tucking blade is mounted within a retaining block 18 which is preferably formed in two members 19 and 21 to define a chamber 22. The members 19 and 21 are secured within a recess 23 formed in the collector cylinder 7 by means of cap screws 24. Each tucking blade 16 is provided with side plates 26—26 and a back plate 27, the side plates 26—26 being formed with slots 28—28 to receive the ends of cross pins 29 mounted transversely in the tucking blade. Each tucking blade is normally held in its forward position with its pins 29 in engagement with the outer ends of the slots 28—28 by means of a block of rubber 31 disposed in the chamber 22 behind the back plate 27. Blocks of rubber 32—32 are provided between the side walls of the chamber 22 and the side plates 26—26 to yieldably resist lateral displacement of the tucking blade 16. As illustrated in Fig. 3 the member 21 of the retaining block 18 is provided with a longitudinally extending slot 33 leading outwardly from the chamber 22, the slot 33 being of sufficient width to permit limited lateral displacement of the tucking blade 16.

A pair of clamping jaws, indicated generally at 36 and 37, are journaled for rotational movement in a bearing block 38 which is secured by means of cap screws 39 in a recess 41 formed in the jaw cylinder 12. As illustrated in Fig. 2, the jaw cylinder 12 may be provided with two or more sets of clamping jaws, if desired, each

16 in folding a sheet of paper 14. A rocker arm 42 is secured to one end of the clamping jaw 36, the free end of the rocker arm being formed with a stud bearing 43 to receive a roller 44. A cam 46 is secured to the inner side of the frame member 11 by means of cap screws 47. A plurality of compression springs 48 are interposed between an abutment shoulder 49, formed on the bearing 38, and the free end of the clamping jaw 36 to normally urge the roller 44 of the rocker arm 42 into engagement with the outer surface of the cam 46. To provide simultaneous clamping or unclamping movement of the clamping jaws, the jaw 36 is provided with a plurality of gear teeth 49 for meshing engagement with gear teeth 51 formed on the jaw 37. A plurality of compression springs 52 are interposed between an abutment shoulder 53 and the free end of the clamping jaw 37 to normally urge said clamping jaw toward its clamping position.

The clamping jaws 36 and 37 are formed with longitudinally extending flanges 56 and 57, respectively, to receive face plates 58 and 59, respectively. The face plates 58 and 59 are secured to their respective flanges by means of cap screws 61 and 62, respectively. As illustrated in Fig. 5, each face plate is formed with a plurality of recesses 63 to receive resilient inserts 64 which are preferably formed of rubber. It will be noted that the forward ends of the inserts 64 project beyond the front faces of the plates 58 and 59, and that the inserts also project upwardly from the side edge 66 of the respective plates. After the inserts 64 are mounted in the recesses 63, the sides of the inserts 64 are flattened at 67 to provide straight edges at 68 for engagement against the paper sheets 14. While the face plates 58 and 59 have been illustrated and described in connection with a plurality of inserts 64, it is contemplated that the face plates could be faced with sheet rubber along their front and side edges, or with a single insert extending throughout the length of a plate.

In the operation of the folding mechanism thus described, the cylinders 7 and 12 are rotated in the direction indicated by the arrows in Fig. 2, and sheets of paper 14 are inserted between the clamping jaws 36 and 37 by means of the tucking blade 16. As illustrated in Fig. 2, the clamping jaws are disposed in their open position by means of a cam 46 to receive sheets to be folded; after which, the clamping jaws are moved to their closed positions, to grip and fold the paper 14, by means of the compression springs 48 and 52. By providing a rubber facing for the clamping jaws, it has been found that the jaws and tucking blade have a longer service life, and that the rubber inserts provide a more positive engagement with the paper 14 during the gripping and folding operation. By providing a resilient mounting for the tucking blade 16, the V-shaped tucking end 17 is free to be moved laterally or inwardly during clamping engagement of the jaws 36 and 37. This movement of the tucking blade serves to permit self-alignment with the clamping jaws. The V-shaped tucking edge 17 facilitates withdrawal of the tucking blade from between the clamping jaws.

Referring now to Fig. 6 in the drawings, the folding mechanism is shown as comprising a jaw cylinder 71 formed with a recess 72 to receive a bearing block 73 which is secured in position by means of cap screws 74. In this form of the invention, a clamping jaw 76 is journaled in the block 73 for movement into and out of engage-

ment with a fixed jaw 77 provided on the block 73. In this form of the invention, a cam 46 and rocker arm 42 are employed to move the clamping jaw 76 to its open position to receive the tucking blade 16 and sheet material 14. A plurality of compression springs 78 are provided to move the clamping jaw 76 to its closed position against the fixed jaw 77. The clamping jaw 76 is shown as comprising a cylindrical bearing portion 81 formed with a longitudinally extending recess 82 to receive a longitudinally extending clamping blade 83 which is formed with a plurality of recesses to receive resilient inserts 84 of the type heretofore described in connection with Figs. 1 to 5. The blade 83 is secured on the cylindrical bearing portion 81 by means of a plurality of cap screws 86. This form of the invention is otherwise similar to the form heretofore shown and described.

20 While this invention has been shown in but two forms, it is obvious to those skilled in the art that it is not so limited but is susceptible of various changes and modifications without departing from the spirit and scope of the claimed invention.

I claim as my invention:

1. In a sheet folding mechanism, a pair of rotatably mounted cylinders having their axes disposed in parallel relation, a pair of jaws mounted on and disposed along the periphery and parallel with the axis of one of said cylinders to grip and fold a sheet of paper inserted therebetween, a tucking blade mounted on the other of said cylinders and having a top edge disposed along the periphery and parallel with the axis of its cylinder, the top edge of said tucking blade being formed V-shape to tuck a sheet of paper between said jaws, said tucking blade being mounted along its sides and bottom edge in soft resilient rubber extending along the periphery and parallel with the axis of the tucking blade cylinder, the rubber acting to yieldably resist lateral and inward movement of said blade during engagement of the latter between said jaws.

2. In a sheet folding mechanism, a pair of rotatably mounted cylinders having their axes disposed in parallel relation, a pair of jaws mounted on and disposed along the periphery and parallel with the axis of one of said cylinders to grip and fold a sheet of paper inserted therebetween, one of said jaws being faced with a plurality of soft resilient rubber inserts disposed at spaced intervals, a tucking blade mounted on the other of said cylinders and having a top edge disposed along the periphery and parallel with the axis of its cylinder, the top edge of said tucking blade being formed V-shape to tuck a sheet of paper between said jaws, said tucking blade being mounted along its sides and bottom edge in soft resilient rubber extending along the periphery and parallel with the axis of the tucking blade cylinder, the rubber acting to yieldably resist lateral and inward movement of said blade during engagement of the latter between said jaws.

3. In a sheet folding mechanism, a pair of rotatably mounted cylinders having their axes disposed in parallel relation, a pair of jaws mounted on and disposed along the periphery and parallel with the axis of one of said cylinders to grip and fold a sheet of paper inserted therebetween, said jaws being faced with a plurality of soft resilient rubber inserts disposed at spaced intervals, a tucking blade mounted on the other of said cylinders and having a top edge dis-

posed along the periphery and parallel with the axis of its cylinder, the top edge of said tucking blade being formed V-shape to tuck a sheet of paper between said jaws, said tucking blade being mounted along its sides and bottom edge in soft resilient rubber extending along the periphery and parallel with the axis of the tucking blade cylinder, the rubber acting to yieldably resist lateral and inward movement of said blade during engagement of the latter between said jaws.

4. In a sheet folding mechanism, a pair of rotatably mounted cylinders having their axes disposed in parallel relation, a pair of jaws mounted on and disposed along the periphery and parallel with the axis of one of said cylinders to grip and fold a sheet of paper inserted therebetween, one of said jaws being movable relative to its companion jaw, said movable jaw being faced with a plurality of resilient rubber inserts disposed at spaced intervals, a tucking blade mounted on the other of said cylinders and having a top edge disposed along the periphery and parallel with the axis of its cylinder, the top edge of said tucking blade being formed V-shape to tuck a sheet of paper between said jaws, said tucking blade being mounted along its sides and bottom edge in soft resilient rubber extending along the periphery and parallel with the axis of the tucking blade cylinder, the rubber acting to yieldably resist lateral and inward movement of said blade during engagement of the latter between said jaws.

5. In a sheet folding mechanism, a pair of rotatably mounted cylinders having their axes disposed in parallel relation, a pair of jaws journaled on and disposed along the periphery and parallel with the axis of one of said cylinders to grip and fold a sheet of paper inserted therebetween, said jaws being provided along their opposing faces with a plurality of resilient rubber inserts, said rubber inserts being arranged at spaced intervals, the inserts on one jaw being disposed in opposing relation with respect to the inserts provided on the other jaw, a tucking blade mounted on the other of said cylinders and having a top edge disposed along the periphery and parallel with the axis of its cylinder, the top edge of said tucking blade being formed V-shape to tuck a sheet of paper between said jaws, said

tucking blade being mounted along its sides and bottom edge in soft resilient rubber extending along the periphery and parallel with the axis of the tucking blade cylinder, the rubber acting to yieldably resist lateral and inward movement of said blade during engagement of the latter between said jaws.

6. In a sheet folding mechanism, a pair of rotatably mounted cylinders having their axes disposed in parallel relation, a pair of jaws journaled on and disposed along the periphery and parallel with the axis of one of said cylinders to grip and fold a sheet of paper inserted therebetween, said jaws being provided along their opposing faces with a plurality of resilient rubber inserts, said rubber inserts being arranged at spaced intervals, the inserts on one jaw being disposed in opposing relation with respect to the inserts provided on the other jaw, a tucking blade mounted on the other of said cylinders and having a top edge disposed along the periphery and parallel with the axis of its cylinder, the top edge of said tucking blade being formed V-shape to tuck a sheet of paper between said jaws, said tucking blade being mounted along its sides and bottom edge in soft resilient rubber extending along the periphery and parallel with the axis of the tucking blade cylinder, the rubber acting to yieldably resist lateral and inward movement of said blade during engagement of the latter between said jaws, spring means to normally hold said jaws in clamping engagement, and cam means to move said jaws out of clamping engagement.

ARTHUR MEADOWCROFT.
